SLIDER FOR SLIDE FASTENERS

Joseph Beckerman, Kew Gardens, N. Y.

Application February 27, 1950, Serial No. 146,535

2 Claims. (Cl. 24—205.15)

1

This invention relates to a pivotally constructed slider for slide fasteners.

The principal object of the present invention is the provision of a slider of the character described which is comprised of pivotally related parts which may be separated into open position or brought together to closed position as and when desired, irrespective of its location on the slide fastener stringers. This feature is extremely important for the purpose of freeing jammed sliders without recourse to special tools and special skills. Sliders which may be disassembled for this very purpose have heretofore been devised and patented. But in most cases, it has been found necessary to completely disassemble the slider in order to accomplish this purpose. In the present invention, however, all that need be done is to swing the two pivotally connected elements of the slider a spaced or desired distance apart and then, when the slider has been freed, to swing said pivotally connected elements back to their original closed, operative position. There are decided advantages in avoiding complete disassembly of the slider.

More specifically, the slider herein claimed comprises a pair of pivotally connected elements and a locking sleeve which engages said elements and locks them in closed operative position. The locking sleeve may be moved to unlocking position in order to free the two pivotally connected elements for relative angular movement to open or inoperative position.

In one form of this invention, the locking sleeve comprises a tubular member having internal screw threads which engage external screw threads on the pivotally connected elements.

In another form of this invention, neither the sleeve nor the pivotally connected elements are provided with screw threads. Instead, the sleeve is slotted to provide clearance for one of said pivotally connected elements when the slot and said pivotally connected element are in registration with each other. When they are out of registration with each other, the two pivotally connected elements are locked in closed position. In neither of these two embodiments of this invention is it necessary to completely remove the locking sleeve from the two pivotally associated elements and in neither case is it necessary to completely separate the two pivotally associated elements from each other.

It is accordingly a correlative object of this invention to provide a slider of the character described having two pivotally connected elements which may be moved into open or closed position relative to each other and which will always be

in proper alignment with each other. This feature naturally flows from the fact that the pivotally connected elements need not be completely disassociated from each other at any time. Similarly, the locking sleeve always remains connected to said pivotally associated elements, or at least one of them, irrespective of the positions of said pivotally associated elements relative to each other.

10 It is a further object to provide a slider of the character described, which is made of but three simple main parts which may be easily assembled, and when so assembled are permanently united to prevent disassembly.

15 Preferred forms of this invention are shown by way of illustration in the accompanying drawing, in which:

Fig. 1 is a perspective view of a slider made in accordance with the first form of this invention, showing the two pivotally connected elements in open position.

20 Fig. 2 is an exploded perspective view thereof showing the two pivotally connected members and the locking member in completely disassembled or unassembled positions, this showing being solely to illustrate the several component parts of the device and not to illustrate one of their possible positions.

25 Fig. 3 is an enlarged longitudinal section through said slider, showing the two pivotally connected elements in open or inoperative position.

30 Fig. 4 is a similar view showing the two pivotally connected elements in closed or operative position.

35 Fig. 5 is a top view of a slider made in accordance with a second form of this invention.

Fig. 6 is a side view thereof.

Fig. 7 is another top view, showing the locking member in unlocking position.

40 Fig. 8 is a view similar to that of Fig. 6 showing one of the pivotally connected elements in open position relative to the other pivotally connected element.

45 Fig. 9 is a longitudinal section through said slider.

50 Referring now to the first form of this invention, and to Figs. 1 to 4 inclusive, it will be seen that slider 20 made in accordance with said first form of the invention, comprises the following elements: a lower jaw 21, an upper jaw 22 pivotally connected to said lower jaw, a pull tab 23 pivotally mounted on said upper jaw 22, and a locking sleeve 24 which is adapted to engage both pivotally connected jaws. The pull tab is, of course, conventional, as are the forward parts

of the two pivotally connected members. Their rearward extensions and the locking sleeve comprise the heart of this invention.

It will be noted that lower jaw 21 is provided with a rearward extension piece 30 which is substantially cylindrical in shape and which is provided with external screw threads 31. At its very back end it is provided with a radially outwardly extending flange 32 which is produced by heading over or upsetting the end of extension 30 after assembly. Extension piece 30 is also provided with a longitudinally extending slot 33 which runs its full length and a transversely extending slot 34 which is formed diametrically thereof, and in its very back end. The two slots 33 and 34 communicate with each other and they are disposed normally to each other.

Upper pivotally connected member 22 is also provided with a rearward extension piece 36, and it will be noted that this extension piece is slightly narrower than the width of slot 33 so that said slot may very conveniently accommodate said extension piece 36. Extension piece 36 is provided with a cross pin 37, the extending ends of which become trunnions which are adapted to be journalled in transverse slot 34 and thereby to enable the upper member 22 to pivot relative to the lower member 21. Extension piece 36 of the upper member may be provided with external screw threads 38 and it will be understood that screw threads are so formed thereon that they are continuous with the screw threads 31 of lower extension piece 30 when the two members 21 and 22 are in closed, pivotally related positions.

Locking sleeve 24 comprises a cylindrical collar having an inwardly extending annular flange 40 formed at its forward end. This annular flange is provided with internal screw threads 42 which are adapted to engage external screw threads 31 and 38 of the two pivotally connected members 21 and 22. (See Fig. 4.) When the locking sleeve 24 is in its forwardmost position on the two pivotally connected members, said pivotally connected members are held in closed position. When said locking sleeve is moved to its rearwardmost position (see Fig. 3), then upper pivotally connected member 22 will be free to pivot away from the lower pivotally connected member 21 to open position. This feature becomes possible by reason of the following arrangement of parts: pin 37 occupies a position forward of the locking sleeve when said locking member is in its rearwardmost position, and the back end of extension piece 36 is rounded as Fig. 2 clearly shows. In other words, when the locking sleeve is moved to its rearmost position on extension piece 30, it disengages the upper member 22 and frees said member for pivotal movement relative to the lower member 21. Locking sleeve 24 cannot disengage extension piece 30 because the outwardly extending flange 32 of extension piece 30 engages the inwardly extending flange 40 of the locking sleeve and functions as a stop member relative thereto. It will be understood that this flange is not formed on the extension piece until after the extension pieces 30 and 36 and the sleeve 24 have been assembled. The extension 36 fits within the longitudinal slot 33 with the trunnions 37 journalled in the transverse slot 34 to properly align jaws 21, 22.

It will be noted in Figs. 3 and 4 that a shoulder 45 is formed between the main body of upper member 22 and its extension piece 36. When locking member 24 is in locking position on the

two pivotally connected members 21 and 22, it abuts shoulder 45 as shown in Fig. 4. It will be understood from this arrangement, that screw threads 38 may, if desired, be omitted from extension piece 36 since the abutment of the locking member against shoulder 45 of upper member 22 will serve to position said upper member relative to the lower member 21. Stated differently, as the construction of the two pivotally connected members is illustrated in the drawing, screw threads 38 and 31 in engagement with screw threads 42 serve to position the upper and lower pivotally connected members relative to each other. Should screw threads 38 be dispensed with, it will be the abutment of the locking members against shoulder 45 that will serve to accurately align the upper and lower members of the slider.

Turning now to the second form of this invention as shown in Figs. 5 to 9 inclusive, it will there be seen that slider 60, made in accordance with said second form of the invention, has no screw threads at all. Its upper jaw 61 is provided with an extension piece 62 which is pivotally connected to extension piece 63 of lower jaw 64 in the same manner as it was in the first form of the invention. Locking member 65 is rotatably mounted on the two extension pieces 62 and 63. It has a cut-out 66 formed therein which is registerable with extension piece 62 of the upper jaw. When locking member 65 is turned from its locking position of Fig. 6 to its unlocking position of Fig. 8, cut-out 66 will register with extension piece 62 and enable said extension piece, as well as jaw 61 with which it is integral, to pivot to open position as shown in Fig. 8. When cut-out 66 is out of registration with said extension piece 62, the slider is locked in closed position. Fig. 9 shows the details of construction of slider 60. It will there be seen that trunnions 70 are connected to extension piece 62 of the upper jaw, and that these trunnions are journalled in slot 71 formed in extension piece 63 of the lower jaw.

It will also be seen in said Fig. 9 that locking member 65 is provided with an inwardly turned flange 73 which projects into an annular groove 74 formed along the line of juncture between extension piece 63 and jaw 64 with which it is integral. It is this flange-in-groove construction which prevents longitudinal movement of the locking member relative to said jaws.

It will be understood that the foregoing is illustrative of the preferred forms of this invention and that other forms as well as modifications of these forms may readily be had within the broad scope and spirit of the invention as set forth in the appended claims.

Having thus described my invention, what I claim as new and desire to secure by Letters Patent, is:

1. A slider for slide fasteners, comprising a pair of top and bottom wall members, rearward extension pieces on said wall members, the bottom wall member extension having a transverse bearing slot in its free end, and having a longitudinally disposed radial slot receptive of substantially the whole body of the bottom member extension, a pair of trunnions carried by the extension piece of the top wall member and rotatably receivable in said bearing slot to constitute a pivotal connection between said extension pieces, and a locking sleeve longitudinally movably embracing said extension pieces, said extension pieces being provided with aligned external screw threads and said locking sleeve being

provided with internal screw threads engageable therewith, a rotation of said locking sleeve in one direction on said screw-threaded extension pieces causing the locking sleeve to move forwardly of said pivotal connection to restrain the extension pieces against relative pivotal movement, and rotation of said locking member in the opposite direction causing said locking sleeve to move rearwardly of said pivotal connection and into unlocking position to enable said extension pieces to engage in relative pivotal movement.

2. A slider in accordance with claim 1, wherein in the locking sleeve comprises a cylindrical member having a radially inwardly extending flange formed at its forward end, the internal screw threads of said locking sleeve being provided on said inwardly turned flange, and wherein in one of the extension pieces is provided with a radially outwardly extending flange on its rearward end which is engageable with the inwardly turned flange of the locking sleeve when said locking sleeve is moved to its rearward position, thereby serving as a stop therefor and

5 preventing disengagement of said locking sleeve from said last-mentioned extension piece.
